UNITED STATES PATENT OFFICE

TIDEMAN M. LILLEBERG, OF CHICAGO, ILLINOIS, ASSIGNOR TO THE NYE TOOL & MACHINE WORKS, OF CHICAGO, ILLINOIS, A CORPORATION OF ILLINOIS

THREAD-CUTTING DEVICE

Application filed April 23, 1928. Serial No. 272,110.

My invention relates to thread-cutting devices of the type in which the thread-cutting elements are carried by a head having a portion forming a journal support for an operating member, such as a lever provided with a ratchet cooperating with ratchet teeth on the head.

One of my objects is to provide a thread cutting device of the general type referred to and employing as the thread cutting element a solid die block which, as commonly constructed, contains an opening therethrough into which the thread-cutters extend, the die block and holding head therefor of which may be readily assembled and disassembled, as desired.

To provide a novel, simple and economical construction of the type above referred to.

To provide a construction of the type referred to, and employing a die block, which shall present the maximum of strength with the minimum amount of metal, and the die block of which may be readily removed and replaced, or another substituted, as desired.

To provide a construction of the type referred to and employing a die block whereby a plurality of die blocks of different sizes assembled with holding heads, respectively, and having openings therethrough of the desired sizes for cooperation with the particular sizes of die blocks used therewith may be interchangeably used with an operating member such as that above referred to and for journal support on the heads; and other objects as will be manifest from the following description.

Referring to the accompanying drawing:

Figure 1 is a view in side elevation of a thread cutting device constructed in accordance with my invention.

Figure 2 is a sectional view taken at the irregular line 2-2 on Fig. 1 and viewed in the direction of the arrows.

Figure 3 is a section taken at the line 3 on Fig. 2 and viewed in the direction of the arrow.

Figure 4 is a view like Fig. 2 of a modification of the die block holding head; and

Figure 5, a similar view of another modification of the die block holding head.

Referring to the particular construction shown, the device comprises a head represented at 6, one end thereof being of reduced diameter as shown at 7 and at which portion it is provided peripherally with ratchet teeth 8, the portion 7 forming a journal support for an operating member 9 shown as comprising a bar 10 connected with and extending outwardly from, a body member 11 containing an aperture 12 therethrough at which it surrounds the journaling portion 7 of the head 6, the member 11 being provided with a ratchet 13 provided with a tooth 14 at which it engages the teeth 8 on the head 6, this ratchet, which is spring pressed toward the teeth 8 by a coil spring 15, having a stem 16 projecting into a position in which it is accessible for retracting the ratchet 13 when desired, which feature is in accordance with common practice.

The cutting element of the device comprises a round die block 17 containing an opening 18 therethrough into which the thread cutting portions 19 of the die block extend in accordance with common practice.

The die block 17 is positioned against the outer face of the larger end 20 of the head 6 and is held in place thereon by a ring 21 internally threaded at one end as represented at 22 at which it screws upon external threads 23 provided about the periphery of the portion or flange 20 of the head, the die block 17 being preferably interlocked with the head 6 to prevent relative rotation of these parts, as for example by means of pins 24 secured in the portion 20 of the head 6 to extend lengthwise thereof with their protruding ends projecting into rearwardly opening recesses 25 in the die block 17.

The head 6 contains an opening 26 extending entirely therethrough coincident with the longitudinal axis of this head, this opening being of slightly larger diameter than the diameter of the space bounded by the teeth of the cutting portions 19 of the die block, the parts being so constructed, as shown that the opening 18 in the die block extends in alignment with the opening 26.

It may be here stated that in the use of the device the operator upon applying it at its die portion to the object to be threaded, oscillates the operating member 9 at its journaling connection with the head 6 to rotate the head and die in clockwise direction in Fig. 3 to effect the cutting of the thread on the object, the opening 26 being of such size as to permit the device to move freely along the object in the thread cutting operation and at the same time permit the object to form a support for the device at its ratchet toothed portion.

Referring to the particular construction of means shown in Figs. 1 and 2 for holding the die block against the face of the head 6, the ring 21 is formed at its outer end with an internal annular tapered surface 27 which flares inwardly, the die block 17 in this instance being tapered at a similar angle toward its outer end as represented at 28. Thus as the ring 21 is screwed to place it firmly wedges the die block 17 in position against the head.

The construction shown in Fig. 4 is the same as that shown in Fig. 2 except that the tapers on the ring 21' and die block 17' and represented at 29 and 30, respectively, are steeper and shorter than in the case of the tapered surfaces 27 and 28 of Fig. 2.

The construction shown in Fig. 5 is the same as that shown in Fig. 2 except that instead of providing for the wedging of the die block against the head by the action of the ring 21'', the die block is held in position by means of the engagement of an inwardly extending annular flange 31 at the outer end of the ring against an annular shoulder 32 formed on the outer face of the die block by peripherally recessing it as shown.

It will be understood that as to all of the forms of structures shown the die block may be readily removed from the head merely by unscrewing the ring and this die block, or a substitute therefor, readily secured in place on the head by replacing the ring.

Furthermore, and this applies particularly to the construction shown in Fig. 2, the ring 21 by having surrounding engagement with the die block serves to reinforce the peripheral wall of the die block and thus the latter may be made much thinner than is possible where the die block is not so reinforced, which makes for durability of structure by the use of the minimum amount of metal.

In practice where it is desired that objects of different diameter be threaded by the device, a plurality of the die-block-equipped heads would be provided, each die block of a different size and each cooperating head with the diameter of its opening 26 proportionately varied, these several die-equipped units, each of which would present a journaling portion of the same external diameter for the operating member 9, being interchangeable wherever but one operating member 9 need be used

for the entire set of the die-equipped heads, it being understood that the die-equipped head may be readily removed from the operating handle upon withdrawing the ratchet from engagement with the teeth on the head. 70

While I have illustrated and described certain particular embodiments of my invention I do not wish to be understood as intending to limit it thereto as the same may be variously modified and altered and the invention embodied in other forms without departing from the spirit of my invention. 75

What I claim as new, and desire to secure by Letters Patent, is:

A thread-cutting device comprising a 80 head having a cylindrical portion, an outwardly extending flange at one end of said portion having peripheral screw threads, an operating means journalled on said cylindrical portion and coaxing therewith, a die block 85 entirely exteriorly of said head having its base in contact with the outer side wall of said flange, whereby said operating member and die block are on opposite sides of the flange to aid in reinforcing the same, a ring surrounding said flange and screw threaded thereto, said ring extending outwardly beyond the flange and overlapping the die block whereby said flange and die block are both peripherally reinforced, said die-block having a 90 tapered peripheral face, said ring also extending inwardly and having a tapered clamping face corresponding to and engaging the tapered face of the die-block to clamp the latter against the flange, and a pin connection detachably holding the die-block against rotation. 95
